CLAIM

The ornamental design for a electric shield to be placed over a baby to retain its body heat, as shown.

DESCRIPTION

FIG. 1 is a front elevational view of the electric shield to be placed over a baby to retain its body heat showing my new design;

FIG. 2 is a rear elevational view thereof;

FIG. 3 is an enlarged left side elevational view thereof;

FIG. 4 is an enlarged right side elevational view thereof;

FIG. 5 is a top plan view thereof;

FIG. 6 is a bottom plan view thereof; and,

FIG. 7 is a perspective view thereof.

*FIG. 1**FIG. 2**FIG. 3*

FIG. 4

*FIG. 5**FIG. 6*FIG. 7
